UNITED STATES PATENT OFFICE.

GEORGE C. HILL, OF BOSTON, MASSACHUSETTS, ASSIGNOR TO REECE SHOE MANUFACTORY COMPANY, OF BOSTON, MASSACHUSETTS, A CORPORATION OF MAINE.

PRESS FOR CUTTING OR PUNCHING SHEET MATERIAL.

Application filed October 18, 1922. Serial No. 595,373.

To all whom it may concern:

Be it known that I, GEORGE C. HILL, a citizen of the United States, residing at Boston, in the county of Suffolk and State 5 of Massachusetts, have invented certain new and useful Improvements in Presses for Cutting or Punching Sheet Material, of which the following is a specification, reference being had therein to the accompanying 10 drawing.

This invention relates to presses for cutting or punching sheet material, more especially to presses of the general type, represented by clicking machines and dinking 15 machines known in the leather and shoe trades, wherein a heavy head or casting is brought down abruptly so as to strike a heavy blow upon a die, which die is laid upon the leather or other sheet material so 20 as to cut the material, the material lying upon a supporting cutting block of substantial area and thickness, which in turn is supported upon rigid portions of the machine beneath, the blow of the head upon the 25 die operating to cut through the material in a single operation or blow, the machine control being arranged so as to permit a single blow with each positioning of the die upon the material.

The object of the present invention is to 30 improve the operation of presses of the kind referred to and more particularly to overcome certain difficulties and defects that have long existed in presses of such kind. The operation of the present invention and 35 its particular advantages will be pointed out hereinbelow in the detailed description of the invention. To the attainment of such objects and advantages, the present invention 40 consists in the novel press and the novel features of combination, arrangement and structure herein illustrated or described.

In the accompanying drawings Figure 1 45 is a side elevation of a press embodying the present invention, the so-called clicking machine being employed for the purposes of illustration, the operator standing at the left in this figure and shifting the die and controlling the machine, for example, as explained in the prior patent of A. R. Schoenky Number 1,295,931, patented March 4, 1919, from which patent the general features of the illustrated machine are largely taken.

Figure 2 is a partial perspective view

showing an ordinary form of cutting die resting upon sheet material or leather which in turn is resting upon the cutting block of the machine shown in Figure 1, the present invention being embodied.

I will first describe some of the well known and general parts of a machine of the class referred to. A four-legged frame 5 gives support to various elements including a heavy and rigidly supported bed or table 6 60 consisting of a casting, usually made separately and rigidly mounted on the frame. Braces 7, or the like, may be provided to give the bed greater rigidity or solidity of mounting. Integral with the frame casting 65 5 are shown at the rear bearings 8 for certain vertically moving parts, as will be described.

It is important in machines of this class 70 to provide relative adjustment as between the bed or lower press member and the head or upper press member. This is sometimes secured by vertical adjustment of the bed and the parts supported upon it. An adjusting wheel 9 is shown for this purpose, 75 the details of which may be ascertained from said prior patent. By this adjustment the machine is able to employ dies of different height or depth, and allowance can be made for variations in dies due to the sharpening 80 of them and other causes.

Located at a higher level than the bed is 85 the upper press member or head 10. In the illustrated embodiment of the invention this head 10, which is a heavy casting, is brought 90 abruptly down upon the die resting upon the work. In some types of die cutting machines the head is supported at its opposite ends and slides upwardly and downwardly 95 in a fixed path, and the present invention can be applied to such machines, but is illustrated as applied to the clicking machine, in which the head or descending presser 10 can be swung to either side so as to be brought over the die in any position and 100 caused to descend in such position.

The head is shown as provided with a rearward extension 11 which in turn has a downward extension 12, and these parts are 105 formed with two bearing portions 13, one above the other. The connection of the head to the frame is through the bearings 13, 13 on the head and the bearings 8, 8 on the frame, and an upright cylindrical pillar 14 engaging all the bearings. Conforming with 110

the disclosure in said prior patent, the pillar 14 is arranged to slide upwardly and downwardly in the frame bearings 8, while the head bearings 13 are arranged to rotate on the pillar; so that the head is capable of the lateral swinging movements as well as the downward and upward operating movements. The particular mechanism for effecting the movements of the pillar forms no part of the present invention and is generally indicated on the drawings by the reference 15. The mechanism is driven by power through a belt pulley 16. The control may be through a lever 17 operated by a foot bar or pedal 18; or, as shown, the control may be performed by hand through a hand bar 19 connected with the bar 18 by rod 20.

The head is shown in its raised position and it normally stands in this position until operated, and usually upon operation the head makes a single descent and rise. This abrupt blow by the heavy casting 10 gives a very effective cutting action. Beneath the head is shown a die 21 resting upon the leather or other material 22 which has been spread out upon a cutting block 23. These parts are shown in both figures. The cutting block is a well known element in such machines and consists usually of wood, or at least presents an upper cutting surface of wood, the grain of the wood preferably running vertically. The cutting block 23 will be seen to have a flat upper surface, trued to the horizontal as exactly as possible, and it is of substantial depth, perhaps five or six inches, so that it possesses considerable inertia resistance of its own. Its weight rests upon the heavy bed casting 6. The material of the cutting block might be changed to some other vibrous or analogous material, capable of being somewhat cut by the die, rather than injuring the die, upon an occasion when one of them must suffer.

According to the present invention, I wholly separate the cutting block 23 from the underlying bed 6 by means of a layer of resilient material 24, for example, a blanket of live rubber which overlies the bed and supports the cutting block. By this arrangement the cutting block, while firmly held in position, is in a sense floating upon the layer of resilient rubber and in effect without any rigid or mechanical connection to the bed beneath. The block is shown surrounded by clamping bars 25 which securely consolidate the wood components of the block, and additional clamps or hooks 26 are shown arranged to hold down the clamps 25 and the periphery of the block. The clamping system, therefore, satisfactorily holds in relative position the cutting block, the resilient element and the bed.

The live rubber layer 24 beneath the deep heavy cutting block is not to be confused

with the use of rubber as a buffer in certain non-analogous arts. It is far more than a buffer in the present use, and advantages and results are secured which are peculiar to the class of machine to which this invention is directed. The rubber blanket in fact does not perform the function of a buffer in the ordinary sense, for the reason that it is closely confined between the block 23 and bed 6, both of large area, and the rubber being substantially incompressible, although resilient, is unable to flow out or bulge out beyond the block or bed as with an ordinary buffer.

Several distinct difficulties and disadvantages have heretofore been well known in clicking, dinking and analogous power presses for dieing out leather or other sheet material by the sharp blow of a heavy head toward a cutting block. These will be pointed out and it will be shown how the present improvement obviates them.

One prior difficulty has been the frequent failure of the die to cut wholly through the work with a single blow of the head, especially with certain kinds of stock being cut, for example several superposed layers of leather, cardboard, etc., or other heavy or resisting material. It is very disadvantageous to apply a second blow or cut in the same cutting operation, because of the possible damage due to the changed conditions, and because of loss of time and output. With the present invention the machine has been made greatly more reliable in this respect, and it is found that a complete cut can be effected with a single blow where frequent difficulty before existed. The character of the work is in this way improved, as well as the output of the machine.

I believe that an action takes place which may be described as follows. The die is always considerably smaller than the bed and block, and even with a larger die the actual cutting areas are relatively small. I believe that a local yielding of the cutting block takes place, namely, at the cutting area, below the die or the cutting portions of the die. This would be different from a general downward yielding of the entire block. The resilient material probably flows laterally from beneath the cutting areas. Therefore, the yield of the rubber at these points would involve the compressing and piling up of the rubber at surrounding points. The entire action would be extremely minute but is apparently effective. The cutting block itself, although of heavy inertia and relatively stiff, may bend minutely at the areas of greatest pressure, for it must be remembered that the descending head is a heavy casting and delivers a very powerful blow. The described minute yielding action of the rubber blanket and cutting block may take place at about

the conclusion of the descent of the head. The inertia of the head compels an appreciable pause before it can reverse and rise. During this minute period I believe that the 5 rubber layer and cutting block, which have yielded locally, make an instantaneous return movement, restoring their normal shapes. This sharp, forcible upward movement constitutes a sort of second or supplemental pressure, insuring completion of the cutting if it has not been completed. In some cases I have even been able to observe what seems to be a double blow, the main blow of the head and the immediate come-back of the block. These actions it is understood would be caused in a case where the cutting resistance is very great. The machine as constructed by me thus adapts itself to the conditions. The more effective 10 cutting action required by the heavier stock is produced, due to the resistance of the stock. When light, easily cut material rests on the cutting block there will be no substantial difficulty in effecting the cutting 15 and the described actions will not take place to the same extent. Whether the above explanation is fully correct the results have been attained in practice, due to the interposition of the live rubber layer. 20

Another difficulty in prior machines has been the liability to break the dies, especially if they have been made too sharp or rendered uneven in resharpening, or in cases where the head and bed are not truly square 25 with each other. The ability of the cutting block to yield locally renders it self-adaptable to such conditions and in practice has effected a substantial saving in dies. A similar difficulty has existed in cases where 30 a heavy blow is struck upon a die upon irregular stock, the die sometimes having been driven into the material of the block to such an extent as to break the edges of the die in removing it.

For similar reasons the present invention 35 saves the face of the cutting block against excessive disfiguration. A much finer adjustment is possible and a complete cut can be assured without the necessity of driving 40 the die into the material of the block. Substantially, the machine can be adjusted so as to drive the die to but not into the wood surface. This is especially true in cases where a relatively heavy blow is required. 45

Owing to these factors, a machine may be 55 constructed with a considerably heavier blow-striking head, and harder blows can be struck. These are real advantages in that much greater efficiency and uniformity of cutting is permitted. The increase of 60 weight of the head and the blow are without added danger to the die and block.

The machine is very substantially freed of 65 excessive noise and jar, which in a machine lacking the present invention might be very disadvantageous and annoying. The rubber blanket tends to insulate the noise and vibration, and in this way a heavier blow may be delivered with less objection.

It will thus be seen that I have described 70 a press of the class referred to, which is more efficient and convenient in action, more durable as regards the machine, the cutting block and the dies, more effective and uniform in the work performed, and delivering 75 better and greater output with less strain on the operator.

Since many matters of design, arrangement, combination and detail may be variously modified without departing from the 80 principles of the present invention, it is not intended to limit the invention to such matters except in so far as specified in the appended claim.

What is claimed is:

In a clicking machine or power press for dieing out leather or like sheet material by a loose cutting die selectively positioned upon the material, the combination of a flat rigid supporting bed, a cutting block of substantial thickness and weight overlying said bed and adapted to give support to the material to be cut, a layer of resilient material between the bed and block and of an area to wholly underlie and yieldingly support the block, means clamping the block and layer in place upon the bed, a heavy head above the block, means mounting said head at one side only in a manner to swing laterally whereby it may be positioned above a cutting die placed selectively upon the material and swung therefrom, and power mechanism operating to cause the head to descend and strike a sudden sharp blow upon the die and then to return.

In testimony whereof, I have affixed my signature hereto.

GEORGE C. HILL.
